CLAIM

The ornamental design for spatula with integral press as shown and described.

DESCRIPTION

FIG. 1 is a front view of the spatula with integral press of the present invention;

FIG. 2 is a left side view of the spatula with integral press depicted in FIG. 1;

FIG. 3 is a right side view of the spatula with integral press depicted in FIG. 1;

FIG. 4 is a bottom view of the spatula with integral press depicted in FIG. 1;

FIG. 5 is a top view of the spatula with integral press depicted in FIG. 1;

FIG. 6 is a rear view of the spatula with integral press depicted in FIG. 1;

FIG. 7 is a bottom, right perspective view of a spatula with integral press depicted in FIG. 1;

FIG. 8 is a rear, right perspective view of a spatula with integral press depicted in FIG. 1; and,

FIG. 9 is a top, right perspective view of a spatula with integral press depicted in FIG. 1.

The broken lines in the drawings illustrate portions of the spatula with integral press that form no part of the claimed design and may depict environmental subject matter only.
